[57] ABSTRACT

Novel biocide compositions having as the active compound an acetophenone of the formula

wherein R is hydrogen, hydroxy and methyl and a method of killing bacteria and fungi.

4 Claims, No Drawings

**METHODS OF COMBATTING FUNGI AND
BACTERIA USING SUBSTITUTED-ALPHA
ISONITROSI-ACETOPHENONES**

STATE OF THE ART

Belgium Pat. Nos. 763,323 and 783,860 which correspond to copending commonly assigned U.S. patent application Ser. No. 255,598 filed May 22, 1972, now U.S. Pat. No. 3,790,687 and U.S. patent application Ser. No. 375,103 filed June 29, 1973 disclose various acetophenones having biocidal activity but they do not describe the compounds of formula I. The compounds of formula I have been described in the literature but their biocidal properties have not been known.

OBJECTS OF THE INVENTION

It is an object of the invention to provide novel biocidal compositions.

It is another object of the invention to provide a novel method of killing bacteria and combatting fungi.

These and other objects and advantages of the invention will become obvious from the following detailed description.

THE INVENTION

The novel biocidal compositions of the invention are comprised of a biocidally effective amount of at least one compound of formula I and preferably a carrier. The compositions may also contain one or more other pesticidal agents. The biocidal compositions of the invention have remarkable bactericidal and germicidal properties which make them useful as industrial biocides for combatting fungi and bacteria which develop in aqueous or non-aqueous media used for the production of diverse industrial products. They are particularly useful for preventing and eliminating bacterial slime in paper-making circuits or in treatment of hides, vegetable tanning liquors, and leathers or in paints, lacquers, glues, ink and lubricating oils.

Suitable compounds of formula I are ω -bromo- ω -isonitroso-acetophenone described by Sassenberg [Ann., Vol. 594 (1955), p. 185], ω -bromo- ω -isonitroso-4-hydroxyacetophenone described by Perti et al. [Indian J. Chem., Vol. 5 (12) (1967), p. 622] and ω -bromo- ω -isonitroso-4-methylacetophenone described by Perti et al. [Proc. Natl. Acad. Sci. India, Vol. 29 pt 3 (1960), p 287].

The compositions may also be incorporated into cosmetic soaps whose yield is capable of preventing the inconveniences caused by the presence of germs, particularly the bacteria on the surface of the human body.

The ω -bromo- ω -isonitroso-acetophenones may be used to combat *Aerobacter aerogenes*, *Pseudomonas aeruginosa*, *Serratia marcescens*, *Bacillus subtilis*, *Staphylococcus aureus*, *Escherichia coli*, *Flavobacterium aquatile* and *Alcaligenes faecalis*, for example.

The compositions of the invention may be in the form of powders, granules, suspensions, emulsions or solutions and can contain, in addition to the active principles, cationic, anionic or non-ionic surface active agents, inert powders such as talc, clays, silicates, kieselguhr, etc., vehicle such as water, alcohols, hydrocarbons or other organic solvents or animal, vegetable or mineral oils.

The solid compositions, presented in the form of a powder for dusting, of wettable powders or granules,

can be prepared by grinding the active compound with an inert solid or by impregnation of a solid support with a solution of the active compound in a solvent which is next evaporated.

A typical biocidal composition of the invention consists of a wettable powder containing 25 percent by weight of ω -bromo- ω -isonitroso-4-hydroxy acetophenone of formula I, 15 percent by weight of Ekapersol S (a condensation product of sodium naphthalene sulfonate), 0.5 percent by weight of Brecolane N.V.A. (sodium alkynaphthalene sulfonate), 34.5 percent by weight of Zeosil 39 (a precipitated synthetic hydrated silica) and 25 percent by weight of Vercoryl S (colloidal Kaolin).

The novel method of the invention for combatting bacteria and fungi comprises contacting bacteria and fungi with a lethal amount of the acetophenones of formula I. The method is particularly useful for preventing the pollution of industrial waters such as aqueous waters in paper-making which may also contain sizing resins. In particular, the novel biocidal method comprises contacting bacteria and fungi with a biocidal amount of the acetophenone compounds of formula I and preferably preventing bacterial slime in aqueous media comprising incorporating a bactericidal amount of the acetophenone compounds of formula I in an aqueous media.

Tests effected in the presence of material such as paper pulp in aqueous suspension with resin sizing in conditions analogous to those used in practice demonstrates the biocidal properties of the acetophenone compounds of formula I.

The compounds of formula I may be prepared by reacting aluminum bromide and acetyl bromide with a compound of the formula

wherein R has the above definition or by reacting alkyl nitrite in the presence of hydrochloric acid with the corresponding ω -bromo-acetophenone or by reacting an alkali metal bromide and hydrobromic acid with a compound of the formula

wherein R has the above definition. The last reaction is preferably effected in an organic solvent such as methanol, ethanol, propanol or isopropanol and the reaction is more complete when terminated by bubbling hydrobromic gas.

ω -chloro- ω -isonitroso-acetophenones of the formula

are known biocides and these compounds, as well as the compounds of formula I, liberate in aqueous media small amounts of the hydacid, namely hydrochloric acid and hydrobromic acid respectively. In order to reduce attack of certain industrial apparatus such as pumps in which the biocides come in contact, it is more advantageous to use the products of formula I which liberate hydrobromic acid rather than hydrochloric acid.

In the following example there is described a preferred embodiment to illustrate the invention. However, it should be understood that the invention is not intended to be limited to the specific embodiment.

EXAMPLE 1

ω -bromo- ω -isonitroso-acetophenone

20 g of $\frac{1}{2}$ -chloro- ω -isonitroso-acetophenone and 20 g of sodium bromide were added to a solution of 51 g of hydrogen bromide gas in 200 ml of ethanol and the mixture was stirred for 17 hours at room temperature. The insolubles were removed by filtration and the filtrate was distilled to dryness under reduced pressure. The residue was dissolved in tetrahydrofuran and the solution was treated with activated carbon, stirred and filtered. The filtrate was distilled to dryness under reduced pressure and the residue was added to methylene chloride. The solution was cooled and the precipitate

STUDY OF THE BACTERICIDAL ACTIVITY

The inhibition of bacteria tested cultivated on a paper pulp medium enriched in bacteria showed the biocidal efficacy of ω -bromo- ω -isonitroso-acetophenone (compound A) and ω -bromo- ω -isonitroso-4-hydroxyacetophenone (compound B). The test used 12.5 gm/liter of paper pulp in an aqueous suspension with resin sizing and the contamination was effected with a bacterial suspension of *Aerobacter aerogenes*. The test compounds were added at concentrations of 50, 25, 12.5, 6.25, and 3.125 ppm and the suspensions were incubated at 37°C. The number of germs in each test was determined before and 45 mn, four and seven hours after the addition of the test compound.

Petri dishes containing a gelled medium thus were seeded and were incubated at 37°C for 48 hours. The number of germs then was determined. The results are expressed in percentage of corrected anti-bacterial effectiveness (CE) of the product to be tested as compared to the non-tested controls. The corrected anti-bacterial effectiveness (CE) is calculated in the following way:

$$CE = \frac{\% \text{ decrease in specimen} + \% \text{ increase in control}}{100 + \% \text{ increase in control}} \times 100$$

TABLE I

Products	Compound A						Compound B				
	ppm M.A.	50	25	12.5	6.25	3.125	50	25	12.5	6.25	3.125
45 mn		76.7	40.5	17.2	0	15.5	99.9	98.2	71.5	0	5.1
4 H		100	82.5	42	4.6	25.2	100	99.8	93.0	53.6	51.7
7 H		100	92.1	41.1	0	11.5	100	99.9	98.4	77.0	58.6

The results of Table I show that compounds A and B possess an high biocidal activity in the test.

Various modifications of the compositions and method of the invention may be made without departing from the spirit or scope thereof and it is to be understood that the invention is to be limited only as defined in the appended claims.

We claim:

1. A method of combatting bacteria and fungi comprising contacting bacteria and fungi with a lethal amount of a bactericidal and fungicidal compound of the formula

wherein R is selected from the group consisting of hydrogen, hydroxy and methyl.

2. The method of claim 1 wherein the bacteria and fungi are in industrial water and the bactericidal and fungicidal compound is added thereto.

3. The method of claim 1 wherein R is hydrogen.

4. The method of claim 1 wherein R is hydroxy.

* * * * *

formed was recovered by vacuum filtration, was washed and dried to obtain 15.5 g of ω -bromo- ω -isonitroso-acetophenone melting at 137°C.

EXAMPLE 2

ω -bromo ω -isonitroso 4-hydroxy acetophenone

10 g of ω -bromo- ω -isonitroso-acetophenone and 10 g of sodium bromide were added to 120 ml of an ethanol solution containing 17 g of hydrobromide gas per 100 ml and the mixture was stirred for 36 hours in a closed container. The insolubles were removed by filtration and after cooling to 10°C, hydrobromide gas was bubbled through the solution for 1 hour. The mixture was distilled to dryness under reduced pressure and the residue was taken up in tetrahydrofuran. The solution was treated with activated carbon, stirred and filtered. The filtrate was evaporated to dryness and the residue was added to methylene chloride. The solution was cooled to 0°C and the precipitate formed was obtained by vacuum filtration and was dried to obtain 7 g of ω -bromo- ω -isonitroso-4-hydroxyacetophenone melting at 190°C.
